VACUUM CLEANER

Filed April 13, 1936

UNITED STATES PATENT OFFICE

2,057,594

VACUUM CLEANER

Frederick Riebel, Jr., Toledo, Ohio, assignor to
Air-Way Electric Appliance Corporation, To-
ledo, Ohio, a corporation of Delaware

Application April 13, 1936, Serial No. 74,050

7 Claims. (Cl. 15—16)

This invention relates to vacuum cleaners and has as its object to provide a vacuum cleaner in which the fan casing is stationary and has a two-part telescoping outlet, one section of which is integral with the fan casing and the other section of which is rigidly attached to the handle so as to move in unison therewith and with the bag which is suspended below the handle and attached to the outlet.

10 Further objects will appear in the perusal of the following detailed description of the invention in connection with the accompanying drawing, in which:

Fig. 1 is a plan view of a vacuum cleaner embodying the invention, parts being broken to better illustrate the construction.

Fig. 2 is a vertical longitudinal sectional view taken on the line 2—2 of Fig. 1, and

Fig. 3 is a transverse vertical sectional view taken on the line 3—3 of Fig. 2.

The invention provides a wheel mounted body unit comprising, generally, the suction chamber 10, suction fan 15, 18 and motor 22. The chamber 10 is provided with suction elbows 11 projecting upwardly from, communicating with, and secured to the bifurcated rear portions 12 thereof. The elbows 11 have wide flanges 13 secured to the side walls 14 of the fan case 15 over the openings 16 in said side walls, and form the fan inlets 16a. The fan case 15 has a central partition wall 17 forming two fan chambers in which the two fan impellers 18 operate. The impellers 18 are mounted upon a shaft 19 which in turn is journaled in bearings 20 mounted in sleeves 21 mounted in the elbows 11.

A motor 22, mounted in a depression 23 in the suction chamber 10, on resilient mountings 24, drives the shaft 19 by means of belts 25, and drives the rotary agitator 26 by means of a belt 27. The agitator 26 embodies flexibly mounted beater elements 28 and brush elements 29. The belt 27 passes through a slot 30 in the top wall of the body 10.

The motor 22 and elbows 11 are covered by a cover 31, having a bumper 32 terminating at its lower end in a headlight hood 33, of soft rubber.

The body of the bumper is vulcanized upon a metal strip which is cut away beneath the hood so the latter may be collapsed without enduring distortion. A headlight and reflector 34 are mounted on the body 10 beneath the cover 32 in position to direct light rays beneath the hood 33 through the opening 35 in the cover.

55 The suction chamber 10 is mounted on front

wheels 36 and rear wheels 37, the latter carried by a frame 38 the forward end of which is pivoted to the knuckle 39 in which is socketed the end of an adjusting screw 40 threaded through a boss 41 on the body 10. The frame 38 is fulcrumed 5 at 42 on the bifurcated conduits 12.

The fan case 15 has a discharge conduit 43 the longitudinal axis of which lies on an arc of a circle having its center on the axis of the pivots 44 of the handle bail 45 of the handle 46. 10

Formed integrally with the bail 45 is the handle socket 47 in which the handle 46 is secured, and which carries the outlet elbow 48 of a swinging discharge conduit 49.

The swinging conduit 49 is telescoped over the 15 conduit 43, and curved to receive the same. The end of the conduit 43 has a flange 50. Threaded into the end of the conduit 43 is a collar 51 between which and the flange 50 is a ring of packing material 52.

The conduit 49 is detachably secured to the elbow 48 as by screws 53, to facilitate by its removal, access to the packing ring 52.

Mounted in the elbow 48 is the bag coupler, 54, which provides communication to the bag 55. 25 The bag 55 is suspended on rods 56 the ends of which are socketed in the web 57 connecting the socket 47 and the elbow 48.

The outer conduit 49 has sufficient range of movement relative to the inner conduit 43 to 30 allow the handle to move from a horizontal to a vertical position. At any position intermediate such terminal positions, the conduits 43 and 49 together form a closed exhaust outlet from the fan chamber to the bag connector. A 35 flexible, stretchable, collapsible tube 58 may or may not be employed to enclose the telescoping conduits 43 and 49. It is secured at its ends to the respective conduits, and seals them against the escape of any dust that might leak past the 40 packing 52. The tube 58 may be removed to clean out the dust collected by it. It is arranged to not interfere with the movement of the conduit 49.

I claim as my invention:

1. In a vacuum cleaner, a body unit including a stationary fan casing, a handle hingedly attached to said body unit, and an exhaust outlet for said fan casing including telescoping arcuate tubular members attached respectively to the 50 handle and to the fan casing, their longitudinal arcuate axes being concentric with the axis of swinging movement of the handle.

2. In a vacuum cleaner, a body unit including a stationary fan casing, a handle hingedly at- 55

tached to said body unit, and an exhaust outlet for said fan casing including telescoping arcuate tubular members rigidly attached to and integrally formed on, respectively, the handle and fan casing, their longitudinal arcuate axes being concentric with the axis of swinging movement of the handle.

3. In a vacuum cleaner, a body unit including a fan casing, a handle hingedly attached to said body unit, and an exhaust outlet for said fan casing including telescoping arcuate tubular members attached respectively to the handle and to the fan casing, their longitudinal arcuate axes being concentric with the axis of swinging movement of the handle, and packing means disposed between said tubular members.

4. In a vacuum cleaner, a body unit including a stationary fan casing, a handle hingedly attached to said body unit, and an exhaust outlet for said fan casing including telescoping arcuate tubular members attached respectively to the handle and to the fan casing, their longitudinal arcuate axes being concentric with the axis of swinging movement of the handle, said outlet being disposed chiefly below the fan casing.

5. In a vacuum cleaner, a body unit including a stationary fan casing, a handle hingedly attached to said body unit, an exhaust outlet for said fan casing including telescoping arcuate tubular members attached respectively to the

handle and to the fan casing, their longitudinal arcuate axes being concentric with the axis of swinging movement of the handle, and a flexible, collapsible tubular covering enveloping the joint between said telescoping members, its respective ends sealed around the respective telescoping members.

6. In a vacuum cleaner, a body unit including a stationary fan casing, positioned in a vertical plane and having its axis extending horizontally and transversely, a handle pivoted to said body unit, and an exhaust outlet for said fan casing including telescoping arcuate tubular members attached respectively to the handle and to the fan casing, their longitudinal arcuate axes being concentric with the axis of swinging movement of the handle.

7. In a vacuum cleaner, a body unit including a stationary fan casing positioned in a vertical plane and having its axis extending horizontally and transversely, a handle pivoted to said body unit on an axis parallel to that of the fan casing, and an exhaust outlet for said fan casing including telescoping arcuate tubular members attached respectively to the handle and to the fan casing, their longitudinal arcuate axes being concentric with the axis of swinging movement of the handle, said outlet lying chiefly below the fan casing and in the plane thereof.

FREDERICK RIEBEL, JR. 30
